(57) **CLAIM**

The ornamental design for a cargo carrier assembly, as shown and described.

DESCRIPTION

FIG. 1 is perspective view of the cargo carrier assembly of the present design;

FIG. 2 is a top view of the cargo carrier assembly of the design of FIG. 1;

FIG. 3 is a bottom side view of the cargo carrier assembly of the design of FIG. 1;

FIG. 4 is an end view of the cargo carrier assembly of the design of FIG. 1; and,

FIG. 5 is a side view of the cargo carrier assembly of the design of FIG. 1.

In the drawings, the broken lines depict environmental subject matter only and form no part of the claimed design.

1 Claim, 4 Drawing Sheets
